No. 894,993.

PATENTED AUG. 4, 1908.

J. A. WILLIS,
LIQUID FUEL BURNER.
APPLICATION FILED NOV. 11, 1907.

UNITED STATES PATENT OFFICE.

JOHN ALBERT WILLIS, OF PALMER, OREGON.

LIQUID-FUEL BURNER.

No. 894,993.

Specification of Letters Patent. Patented Aug. 4, 1908.

Application filed November 11, 1907. Serial No. 401,709.

To all whom it may concern:

Be it known that I, JOHN ALBERT WILLIS, citizen of the United States, residing at Palmer, in the county of Multnomah and State of Oregon, have invented certain new and useful Improvements in Liquid-Fuel Burners, of which the following is a specification.

This invention has relation to a type of burner for utilizing liquid fuel, such as gasolene, naphtha, coal oil, etc., and which may be employed either in a cook stove or in a heating stove, according as the burner is to be arranged in a horizontal or in a vertical position, the construction of the burner being substantially the same in both forms, the only difference being in the arrangement of the flame outlets, which in the burner for cook stoves extend lengthwise and in the burner designed for heating stoves run crosswise of the burner.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a burner designed for cook stoves embodying the invention. Fig. 2 is a vertical central longitudinal section. Fig. 3 is a view similar to Fig. 2 of a modification, showing the burner adapted for heating stoves and designed to be arranged vertically. Fig. 4 is a detail perspective view of an end portion of a wick, showing the metal protectors fitted to the tip thereof, the band protector being moved back from the tip.

Corresponding and like parts are referred to in the following description and indicated in all the views of the drawings by the same reference characters.

The burner embodies in its construction, a pipe 1 for containing a quantity of liquid fuel, and said pipe may be connected with a font, tank or the like for supplying the liquid fuel continuously, thereby obviating the necessity for charging the burner at intervals. The pipe 1 is provided in its sides

with perforations 2 through which the oil passes to supply that consumed when the burner is in operation. A cylinder 3 is fitted upon the pipe 1 and is spaced therefrom, said space being closed at its ends and adapted to be filled with any material either of a fibrous or granular nature. The pipe 1 is likewise filled with an absorbent, such as mineral wool or cotton waste. The cylinder 3 is provided with openings 4 in its sides, said openings being covered by wire gauze 5 to prevent the passage therethrough of the granular material employed for filling the spaces. A double walled cylinder 6 encircles the cylinder 3 and is spaced therefrom, the ends of the space being closed so as to retain the sand or granular material filled therein. The space between the inner and outer walls comprising the double walled cylinder 6 is closed at its ends and is filled with either asbestos or fire clay or any other refractory material. Openings 7 are formed in the sides of the double walled cylinder 6 and extend through both shells thereof and receive tubes 8 which constitute the flame outlets and are fitted with wicks 9, the inner ends of said wicks entering the space formed between the cylinders 3 and 6 and having the granular filling material 10 surrounding the same. The openings 7 extend lengthwise of the burner, as indicated in Figs. 1 and 2, and crosswise of the burner, as shown in Fig. 3, whereby the latter may be arranged in vertical position.

In constructing the burner, suitable material may be employed, such as sheet or plate material, or tubing of different sizes cut into requisite lengths and assembled substantially as specified. When the burner is to be used for a short length of time only, as in a cook stove, the pipe 1 may be charged with a quantity of oil, but when the burner is to be used continuously for a great length of time, the pipe 1 is to be connected with a tank or reservoir so as to receive a constant supply of liquid fuel therefrom. For catching any overflow, a drip pan 11 is fitted to the burner and is supplied with a bail 12, whereby the burner may be placed in position in the fire pot or a cook stove or removed therefrom when desired.

In the modification shown in Fig. 3, the oil pipe 1 has its upper portion perforated, only, to insure supply of oil to the topmost flame outlets, sufficient oil passing downward to the lower flame outlets. The tubes

8 are preferably inclined upwardly towards their outer ends at an angle of about forty-five degrees, thereby preventing waste of oil and insuring proper supply to the wicks
5 Each of the wicks is provided with a tip 13 and a band 14, each constructed of foraminous or reticulated material. The parts 13 and 14 constitute protectors to prevent a too rapid burning away of the wicks and also to
10 equalize the heat by distributing the same by conduction and convection.

Having thus described the invention, what is claimed as new is:

- 15 1. In a burner for consuming liquid fuel, the combination of a perforated pipe, a double walled cylinder fitted upon said pipe and spaced therefrom and having said space supplied with filling material and closed at opposite ends, said cylinder having corresponding openings in both walls, tubes fitted in the openings of the walls of the said cylinder, and wicks fitted in said tubes and having their inner ends extended into the space between the double walled cylinder and per-
- 20 25 forated pipe embedded in the filling material.
2. In a burner of the character specified, the combination of a perforated pipe, a cylinder fitted upon said pipe and spaced therefrom and having the space closed at its ends, said cylinder having perforations in its sides,

wire gauze fitted upon the cylinder and closing and protecting the openings thereof, and a second cylinder provided with flame outlets fitted upon the perforated pipe and spaced from the first-mentioned cylinder and having the ends of said space closed, the space between the two cylinders being supplied with filling material.

3. The herein described burner comprising a perforated pipe, a perforated cylinder fitted upon said pipe and spaced therefrom and having the space closed at its ends, wire gauze fitted to said cylinder and extended over the perforations thereof, a double walled cylinder fitted upon the perforated pipe and spaced from the first-mentioned cylinder and having the space closed at its ends and supplied with granular filling material, tubes fitted in the openings of the walls or shells comprising the double walled cylinder, and wicks fitted in said tubes and having their inner ends extended into the space formed between the first-mentioned and double walled cylinders.

In testimony whereof I affix my signature 55 in presence of two witnesses.

JOHN ALBERT WILLIS. [L. s.]
